Inventor:
Joseph B. Okey.

UNITED STATES PATENT OFFICE.

JOSEPH B. OKEY, OF INDIANAPOLIS, INDIANA, ASSIGNOR TO HIMSELF AND WM. H. KENDRICK, OF SAME PLACE.

STRAW-CUTTER.

Specification of Letters Patent No. 25,469, dated September 13, 1859.

To all whom it may concern:

Be it known that I, JOSEPH B. OKEY, of the city of Indianapolis, county of Marion, and State of Indiana, have invented a new and useful Improvement in Straw-Cutters; and I do hereby declare the following to be a full and exact description of my invention, reference being had to the accompanying drawing and the letters of reference marked 10 thereon.

The nature of my invention consists in providing a common cutting box with a movable bottom—said bottom having a vibratory movement, forward and back, by 15 means of which the straw is carried up to the knife. This bottom is moved by two cams or projections, upon the end of the lever which operates the gate, carrying the knife—said cams operating in a groove, or notch, 20 cut in a horizontal bar, and this bar connected to the bottom by a yoke.

In order that persons who are skilled in the construction of cutting boxes may make and use my invention, I will now proceed to 25 describe the same.

I construct a box similar to other cutting boxes, as a receptacle for the straw—with the difference that mine has a sliding bottom D;—to this bottom is attached the yoke C;—30 on the off side of the box, a sliding bar B, is attached to the yoke C;—

I, is the knife gate, which carries the knife K;—A, is the lever which moves the knife gate I, up and down;—

H, is an adjustable slot, which accommodates itself to the gate pivot that moves the gate;—

At the farther end of the gate lever A, will be seen two small projections, or cams—40 one on each side, and at opposite edges of the flattened end of this lever;—this broad and flat end of the lever describes a portion of a circle when in operation, and bears such a relation to the sliding bar B, that it 45 moves these cams alternately through a notch or groove cut in the end of the sliding bar B, and so gives an alternate movement of said bar—up toward the knife, and then back from it. These cams are seen at 50 F, and G. The cross piece M, M, is de-

signed to cut against, and is rubbed by the knife K.

The operation of this machine is simple;—viz—by taking hold of the lever A, and raising it up, the cam F, (which is no more than 55 an inclined plane) presses the sliding bar B—(and with it, the yoke C, and sliding bottom D)—up toward the knife K, bringing the straw in the box, up far enough to receive the first cut;—then by pressing the 60 handle of this lever down, it drives the knife down through the straw, and, just at the point where the cut is completed, the cam G comes in contact with the sliding bar B, so as to return the bottom D back to the place 65 of beginning, when it is ready to carry the straw up for another cut—the packing board E, performing the office of holding the straw down firmly to the moving bottom all the while. Thus, it will be seen that when it is 70 desirable to move the bottom either way, it is done direct, and with a slight expenditure of power.

Now, I am aware that a sliding bottom in cutting boxes, is not new,—as, for example—75 in the cutting box of W. W. Hollman, patented March 30th 1858;—I am aware also, that said Hollman claims—“the combination of” a “movable bottom”—with a cam shaft, and, cams thereon located beneath the knife, 80 and, operated by a crossbar in the knife gate—said cams producing a reciprocating movement in the sliding bottom by a connecting rod projecting from said cam shaft (at an angle of thirty degrees) back, and up, to the 85 underside of said bottom;—Such a device I disclaim wholly—but,

What I do claim, is—

1. The combination of sliding bar B, when constructed as set forth, with yoke C, and 90 vibrating bottom D; and—

2. The combination of cams F, and G, with lever A, when constructed and used as described:—all operating substantially as, and for the purposes mentioned in the fore- 95 going specification.

JOSEPH B. OKEY.
